SHOE FORMING AND PRESSING MACHINE

Milton L. Dodge and Allen A. Dodge, Newburyport, Mass., assignors to Compo Shoe Machinery Corporation, Boston, Mass., a corporation of Delaware

Application November 14, 1949, Serial No. 127,144

11 Claims. (Cl. 12—51)

1

This invention relates to machines for forming and pressing the uppers of shoes.

As the forming and pressing has heretofore been performed, it has been usual practice to pull the shoe tongues out from between the pressing members so that these tongues are not treated during the pressing operation. Should they be left in position, undesirable imprints thereon of the eyelets and eyelet stays would result with machines as heretofore constructed.

An object of the present invention is to provide means by which the tongue, as well as other portions of the shoe upper, may be formed and pressed during the one operation and without producing the undesirable impression of the eyelets or other parts on the tongue. This is accomplished, in accordance with the present invention, by interposing between the tongue and the eyelet stays a member which presents a smooth contour to the tongue, and which through the pressure imparted during the pressing operation on the other shoe upper portions, will also apply smoothing and setting pressure to the tongue, and, if desired, will crease the tongue longitudinally centrally.

Another object is to provide means facilitating the placing of the shoe with its tongue beneath the tongue-engaging member, or causing the tongue-engaging member to be introduced into operative position and withdrawn after the pressing and setting operation.

For a complete understanding of this invention, reference may be had to the accompanying drawings in which

Figures 1, 2 and 3 are fragmentary front and side elevational views and a top plan view, respectively, of a shoe forming and pressing machine provided with a tongue-engaging and pressing element and embodying the invention.

Figure 4 is a view partly in side elevation and partly broken away and in section and to a larger scale than Figures 1 to 3, inclusive, showing a shoe positioned on an inner shoe form and with the tongue-engaging elements of Figures 1 to 3, inclusive, in operative position.

Figure 5 is a detail sectional view on line 5—5 of Figure 4.

Figure 6 is a fragmentary perspective view showing the tongue-engaging and pressing element of Figures 1 to 5 positioned adjacent to and preparatory to insertion into a shoe to be pressed.

Figure 7 is a fragmentary side elevation of an inside pressing form and a tongue-engaging element of modified construction.

Figure 8 is a detail sectional view on line 8—8 of Figure 7.

2

Figure 9 is a fragmentary side elevation of a shoe forming and pressing machine showing a further modified construction of tongue-engaging element and actuating means therefor.

Figure 10 is a fragmentary view partly in side elevation and partly broken away and in section showing a shoe positioned on the machine of Figure 9, and with the tongue-engaging element advanced to overlie the shoe tongue.

16 Figure 11 is a detail sectional view to a larger scale on line 11—11 of Figure 2.

Figure 12 is a perspective view of a shoe as it appears after the pressing operation.

Referring first to Figures 1 to 5, and more particularly to Figures 1, 2 and 3, a shoe pressing and forming machine of the type shown in the Dodge Patent No. 2,211,054, granted August 13, 1940, for Method of and Apparatus for Treating Shoe Uppers, is illustrated, this machine comprising a gooseneck portion 1 rising from a support 2, this gooseneck portion supporting at its forward and upper end an inner rigid shoe pressing form 3. This inner shoe pressing form has convex side faces 4 merging in a central downwardly inclined apex 5, which is located substantially in the central plane of a shoe shown in dotted lines in Figure 2 at 6, placed thereover. The upper of such a shoe may be pressed against the side faces 4, as by a pair of outer pressing members 7, each carried at the upper end of a lever 8. These levers 8 are fulcrumed at 9 to the support 2 on either side of the shoe form and may be brought into pressing engagement with the shoe on the form by any suitable means such as that shown in the Dodge Patent No. 2,211,054, to which reference has been made.

35 Heretofore when pressing a shoe on such a form, it has been customary to remove the tongue of the shoe from its position in order that the pressing operation might not press the eyelet stays of the shoe against the tongue and mark the tongue by reason of the varying thickness of the eyelet stay or by reason of the eyelets set therein.

40 In accordance with the present invention, a sheet material member 10, which may well be of metal and of sufficient thickness and stiffness to prevent pressure of the eyelets and stays thereon from transmitting impressions to the tongue, and which is bent centrally to form a longitudinal apex 11 with side wings 12 extending laterally therefrom, is interposed between the tongue 15 of the shoe, shown best in Figures 4, 5 and 6, and the eyelet stay portions 16, which for clarity are shown in Figure 6 as turned back to expose the tongue. The side wings 12 of this sheet material

member are arranged substantially parallel to the side walls 4 of the shoe support form and they prevent contact between the eyelet stays and the tongue during the pressing operation, which presses the eyelet stay portions against the member 10, the member 16 against the tongue 15, and the tongue 15, as well as the other parts of the shoe upper, against the form 3. Certain of the pressing members, as, for example, the form 3 may be heated as by the use of electrical heating units as is well known in the art.

For the purpose of facilitating the introduction and removal of the member 10 between and from pressing position, it is shown in these figures as carried by a rod 20, one end of which is secured to the rear end of the member 10 and which extends substantially perpendicular to its apex 11. This rod 20 is slidable through a pin 21 rockably carried between the jaws 22 of a lever 23, which may be fulcrumed as at 24 to the gooseneck portion 1 to swing substantially in the central plane of the shoe form 3. As shown best in Figure 3, this lever 23 is bifurcated so as to provide a pair of spaced hub portions 25 bearing on opposite sides of the central web 26 of the gooseneck portion. A pair of coil springs 27 engaging at their upper ends around posts 28 projecting outwardly from the rear end of the lever 23 and secured at their opposite ends to the gooseneck 26, as at 29, normally hold the forward end of the lever 23 elevated with the member 10 in the full line position of Figure 2 where the member 10 is held in substantially perpendicular relation to the lever 23. By grasping the handle 30 on the outer end of the rod 20, this rod may be pulled forwardly and the forward end of the lever 23 moved downwardly toward the dotted line position of Figure 2, and the member 10 passed edgewise in between the eyelet stay portions 16 and the tongue 15 from which position it may be moved down into close engagement with the tongue 15 as shown in Figures 4 and 5. Coil springs 32 surrounding the rod 20 and bearing on opposite faces of the pin 21 normally tend to center this rod with relation to the pin 21, but permit the member 10, by manipulation of the handle 30 by the operator, to be positioned as shown in Figures 4 and 5, preparatory to a shoe pressing operation. The member 15 is then held in this lowered position as by a spring latch 33 carried by the lever 23 engaging beneath an inclined latch plate 34 carried by the gooseneck 26 as best shown in Figure 11. This latch has a portion 38 provided with a lateral recess housing a downwardly spring pressed pin 35 which normally lies in the path of motion of a finger 36 carried by one of the outer pressing members 7. This finger 36 has an inclined face 37 which engages and retracts the pin 35 when the outer pressing members 7 are brought inwardly into shoe pressing position, but after pressing has been effected and the outer pressing members 7 are moved outwardly the finger 36 engages against the inner face of the pin 35 and retracts the latch 33 from the latch plate 34 which permits the springs 27 to lift the member 10 away from the shoe, whereupon the pressed shoe may be removed readily from the inner form. In the retracted or lifted position the member 10 is entirely away from a shoe on the form so that it offers no obstruction to the placing or removal of the shoe. The possibility of a shoe or its tongue being improperly positioned when the pressing action is effected is thus minimized.

In some cases and with some shoe materials,

particularly where the shoe tongue is of some stiffness, a simple construction and mounting of the member 10 for the pressing operation may be employed. As shown for example, in Figures 7 and 8, the sheet material member 10a may be provided with a rearwardly projecting resilient portion 40 which may be directly secured as by screws 41 to the forward face of the base portion 42 of the inside form 3 in such a manner that the member 10a is normally spaced from the side walls 4 of the form by an amount amply sufficient to permit the insertion of the tongue therebetween when the shoe is placed upon the form 3. During such placement the eyelet stay portions are removed sufficiently by the operator to permit them to pass over the outer face of the member 10 so that when the shoe is finally positioned on the form, the member 10a will lie between the outer face of the tongue and the inner faces of the eyelet stays substantially in the same position as the member 10 in Figures 4 and 5. During the single pressing operation the side jaws press the eyelet stays against the member 10a and the member 10a against the tongue and the tongue against the inner form, the resilient portion 40 yielding inwardly. After the pressing operation has been performed, the shoe may then be removed from the form by merely pulling it forwardly off therefrom.

In Figures 9 and 10 a further modification is shown in which the member 10b is mounted for motion from and to operative relation with the inside presser form 3b. The inside presser form 3b is shown as supported on a horizontal bar 43 supported in the upper end of the arm 46 upstanding from the bracket 47 to which the side presser carrying arms 8 are pivoted. The arm 46 carries on its upper end a bracket 48 through which is slidably mounted in a downwardly and forwardly direction, a bar 49 to the forward end of which is secured a bar 50 preferably flexible, the forward end of which, in turn, is secured to the rear end of the member 10b. This member is normally held retracted from operative position, as by a coil spring 51 surrounding the bar 49, and reacting between the bracket 48 and a head 52 at the rear end of the bar 49. This head 52 carries a cam follower roll 53 upon which may bear the upper end of an actuating lever 54. This actuating lever 54 is fulcrumed at 55 on a rearward extension of the bracket 47. On its lower end it is provided with a cam face 56 upon which bears a cam follower roll 57 at the rear end of an actuating lever 58. This actuating lever 58 is fulcrumed at 59 on the support 47 and forwardly of its fulcrum it is connected through a link 60 with the lower end of a vertically slideable bar 61 connected through pivoted toggle links 62 to the lower end of the arms 8. By pressing downwardly on a handle 63 at the forward end of the lever 58, the rear end of this lever is lifted, which acts to press the lower end of the lever 54 rearwardly, rocking this lever into the dotted line position shown in Figure 9, and forcing the rod 49 forwardly to bring the member 10b edgewise into the operative position shown in Figure 10 with its member 10b positioned above the shoe tongue 15 and beneath the eyelet stays which are, however, not shown in this figure. Further downward motion of the handle 63 after taking up lost motion of the pin 64 in the slot 65 of the bar 61 acts to "make" the toggle of links 62 and bring the side presser members 7 inwardly to press the shoe against

the form with the eyelet stays pressed against the member 10b, the member 10b pressed against the shoe tongue, and the shoe tongue pressed against the inside form. On lifting the handle 63, the reverse operation takes place, the side presser members first being retracted, followed by retraction of the member 10b, after which the pressed shoe may be moved from the inside presser form and a shoe to be pressed placed thereon for a succeeding pressing operation.

The action of any of the machines shown in this application is to thin and turn inwardly the top edge portions of the shoe, shrinking the lining and pressing the edges of the outer thereover, and to perform the same operation on the eyelet stay portions and on the tongue, and to crease the tongue centrally longitudinally, all in a single operation.

From the foregoing description of certain embodiments of this invention, it will be evident to those skilled in the art that various changes and modifications may be made therein without departing from the spirit or scope of the invention.

We claim:

1. The combination with a rigid inside form over which a shoe having a tongue and an eyelet stay may be placed, means engageable with the outside of the shoe for pressing the shoe upper against said inside form, of an element adapted to be interposed between the tongue of the shoe and said eyelet stay for the pressing operation to thereby prevent the eyelet stay from marking the tongue and means supporting said element for motion between operative interposed position and a retracted inoperative position where it offers no obstruction to the removal and proper positioning of a shoe with respect to said form.

2. The combination with a rigid inside form over which a shoe having a tongue and an eyelet stay may be placed, means engageable with the outside of the shoe for pressing the shoe upper against said inside form, of a sheet member of inverted V contour adapted to be interposed between the tongue and eyelet stay of the shoe and with the apex of the V extending longitudinally substantially centrally of said tongue to thereby prevent the eyelet stay from marking the tongue during the shoe upper pressing operation and means supporting said element for motion between operative interposed position and a retracted inoperative position where it offers no obstruction to the removal and proper positioning of a shoe with respect to said form.

3. The combination with an inside form for receiving and supporting the upper of a shoe right side up, said shoe having a tongue and an eyelet stay, a support carrying said form, and means engageable with the outer face of an upper of a shoe on said form for pressing the shoe upper against said form, of a sheet material member, and means supporting said member from said support for edgewise motion from and to a position lying between said tongue and eyelet stay to be in such position during the pressing of said upper against said form.

4. The combination with an inside form for receiving and supporting the upper of a shoe right side up, said shoe having a tongue and an eyelet stay, a support carrying said form, and means engageable with the outer face of an upper of a shoe on said form for pressing the shoe upper against said form, of a sheet material

member, a lever pivoted to said support, and means carrying said member from said lever for motion to bring said member from and to a position lying between said tongue and eyelet stay to be in such position during the pressing of said upper against said form.

5. The combination with an inside form for receiving and supporting the upper of a shoe right side up, said shoe having a tongue and an eyelet stay, a support carrying said form, and means engageable with the outer face of an upper of a shoe on said form for pressing the shoe upper against said form, of a sheet material member, a lever pivoted to said support to swing in substantially the central longitudinal plane of said form, and a rod pivotally and slidably connected to one arm of said lever and secured at one end to the rear end of said member, whereby on swinging of said rod and lever said member may be moved from and to a position between said tongue and eyelet stay.

6. The combination with an inside form for receiving and supporting the upper of a shoe right side up, said shoe having a tongue and an eyelet stay, a support carrying said form, and means engageable with the outer face of an upper of a shoe on said form for pressing the shoe upper against said form, of a sheet material member, a lever pivoted to said support to swing in substantially the central longitudinal plane of said form, a rod pivotally and slidably connected to one arm of said lever and secured at one end to the rear end of said member, whereby on swinging of said rod and lever said member may be moved from and to a position between said tongue and eyelet stay, and yielding means tending to center said rod with the forward end of said member extending toward the toe portion of a shoe on said form.

7. The combination with an inside form for receiving and supporting the upper of a shoe right side up, said shoe having a tongue and an eyelet stay, a support carrying said form, and means engageable with the outer face of an upper of a shoe on said form for pressing the shoe upper against said form, of a sheet material member, a bar supported for longitudinal sliding motion on said support substantially parallel with the top face of said form, said bar carrying said member at its forward end for motion into and out of position between said tongue and stay as said bar is moved, means for pressing the upper of a shoe on said form, and means for moving said bar to position said member between said tongue and stay and to then actuate said pressing means to press the shoe upper against said form.

8. In combination, a rigid form over which a shoe having a tongue and an eyelet stay may be placed, and a sheet material member normally yieldingly spaced from said form sufficiently to avoid interference with the free placing and removal of a shoe with respect to said form and movable from such spaced position to a position engaging said tongue with its under face in position for said eyelet stay to engage the outer face thereof.

9. In combination, a rigid form over which a shoe having a tongue and an eyelet stay may be placed, a sheet material member normally yieldingly spaced from said form sufficiently to avoid interference with the free placing and removal of a shoe with respect to said form and movable from such spaced position to a position engaging said tongue with its under face

in position for said eyelet stay to engage the outer face thereof, and means for pressing the eyelet stay of a shoe on said form against said member, said member against said tongue and the shoe upper including said tongue against said form.

10. In combination, a rigid form over which a shoe having a tongue and an eyelet stay may be placed, said form having convex side faces merging in a substantially central apex sloping toward the forward end of said form, said convex side faces being positioned inwardly of the eyelet stay portions of a shoe placed on said form, a sheet material member shaped to lie substantially parallel to said side faces and mounted for motion between a retracted position in which it offers no obstruction to the removal and proper positioning of a shoe with respect to said form and a position engaging the outer face of a shoe tongue while said eyelet 20 stay portions lie on the outer face of said member, and means pressing said eyelet stay against said member and said member and said upper including said tongue against said form.

11. The combination with an inside form over 25

which a shoe having a tongue and an eyelet stay may be placed, and means engageable with the outside of the shoe for pressing the shoe upper against said inside form, of an element 5 adapted to be interposed between the tongue of the shoe and said eyelet stay for the pressing operation to thereby prevent the eyelet stay from marking the tongue, and means actuatable to first interpose said element between the tongue and eyelet stay of a shoe on said inside form and then to press said outside engaging means against the shoe including the eyelet stay against said element, said element against said tongue and said tongue against said inside form.
